US00D472392S

(12) **United States Design Patent** (10) Patent No.: **US D472,392 S**
Clingman, Jr. (45) Date of Patent: ** Apr. 1, 2003

(54) **PARTIAL OVAL MATBOARD PORTIONS IN THE TOP-LEFT AND LOWER-RIGHT CORNERS THEREOF**

Primary Examiner—Nelson C Holtje

(76) Inventor: **Eugene Calvin Clingman, Jr.**, P.O. Box 166, Hathaway Pines, CA (US) 95233

(57) **CLAIM**

(**) Term: **14 Years**

The matboard design partial oval matboard portions in the top-left and lower-right corners thereof, as shown and described herein.

(21) Appl. No.: **29/152,514**

DESCRIPTION

(22) Filed: **Dec. 26, 2001**

The partial ovals are incorporated into matboard commonly used to frame a piece of artwork. The design incorporates dual ovals, one in the top-left corner, the other in the lower-right corner, which are used to frame text within the framed art piece. The matboard on which the design is incorporated may be square or rectangle.

(51) LOC (7) Cl. **06-07**

FIG. 1 is a front elevational view of partial oval matboard portions in the top-left and lower-right corners thereof which is horizontally oriented in a rectangular format.

(52) U.S. Cl. **D6/300**

FIG. 2 is a front elevational view thereof which is vertically oriented in a rectangular format; and,

(58) Field of Search .... D6/300-314; 24/67 CF; 40/777-778

FIG. 3 is a front elevational view thereof which is oriented in a square format.

(56) **References Cited**

The broken line showing of environmental structure is for illustrative purposes only and forms no part of the claimed design.
